INDEXING MECHANISM

Arthur Claud-Mantle, Trumbull, Conn.; Gladys Claud-Mantle administratrix of said Arthur Claud-Mantle, deceased

Application November 6, 1956, Serial No. 620,629

5 Claims. (Cl. 74—820)

The present invention relates to an indexing mechanism, particularly for installation in various types of machine tools as, for instance, metal drawing and forming presses, drilling and tapping machines, etc., an object being to provide an indexing mechanism having a high degree of accuracy and in which there are a minimum of moving parts subject to wear or misalignment.

A further object is to provide a dialing mechanism adapted to impart intermittent fractional movement to a dial of relatively large diameter.

Other objects and advantages of the invention will become apparent from a consideration of the following detailed description taken in connection with the accompanying drawings wherein a satisfactory embodiment of the invention is shown. However, it will be understood that the invention is not limited to the details disclosed but includes all such variations and modifications as fall within the spirit of the invention and the scope of the appended claims.

In the drawings:

Fig. 1 is a plan view of an indexing mechanism according to the invention, the same being shown mounted upon the table of a press;

Fig. 2 is a side elevation as seen from the left in Fig. 1;

Fig. 3 is a view partially in side elevation and partially in section taken along the line 3—3 of Fig. 1;

Fig. 4 is a front elevation, on an enlarged scale, showing the dial operating cam of the invention in its relation with the dial pins at the beginning of an indexing operation;

Fig. 5 is a plan view of the cam in the position as seen in Fig. 4;

Fig. 6 is an end view of the cam as seen from the left in Fig. 4;

Fig. 7 is an end view of the cam as seen from the right in Fig. 4; and

Fig. 8 is a front elevation similar to Fig. 4, and showing the cam moved through a partial revolution to the point where the indexing movement of the dial is completed.

Referring to the drawings, the indexing mechanism, according to the illustrated exemplary embodiment of the invention, comprises a base frame 10 provided with a forward pedestal part 11 having a bearing mounting clamp portion of split collar type 12, adapted to be clamped by a screw 13 mounted in the forward wall of the pedestal part, and which secures a ball bearing unit 14 in which the vertical post 15 of the circular dial plate 16 is secured. The frame is provided along each side with an outwardly extending flange 17 for attachment to the table 18 of the press or other suitable machine by means of screws 19, the particular machine partially illustrated being provided with a vertical column or post 20 which may mount any suitable machine mechanism as, for instance, the head of a drilling and tapping press or the like.

A pair of side arms 21 and 22 extend rearwardly from

2

the pedestal part 11 and are connected by a web-like platform 23 rearwardly spaced from the dial and upon which certain parts of the mechanism, hereinafter more fully described, are mounted. Intermediate the ends of the respective arms 21 and 22 there are provided split collar bearing mounting portions 24 and 25, in which bearing bushings 26 and 27 are clamped by tightening of clamping screws 28 and 29, a horizontal cam shaft 30 being journaled in these bushings. The shaft 30 is adapted to be continuously driven during operation of the mechanism, and for this purpose is provided upon one end with a sprocket gear 31 connected by a sprocket chain 32 to a sprocket gear 33 provided upon the shaft 34 of a reduction gear type electric motor 35 mounted upon a platform 36, this platform being mounted for angular adjustment upon the end of the arm 21 by means of a shaft 37 secured at its respective ends in a clamping sleeve 38 of the arm 21 and a clamping sleeve 39 projecting rearwardly from the plate 36, this arrangement permitting convenient engagement or disengagement of the sprocket chain and the desired degree of tension to be applied to the sprocket chain.

The mechanism illustrated is adapted to impart eighteen successive fractional movements to the dial for each revolution of the dial, and for this purpose is provided at its periphery with eighteen equally spaced radially extending pins 40 of circular cross section. Obviously, any number of pins may be provided, depending upon the desired number of indexing movements required for a particular operation. The axis of the cam shaft 30 is in the same horizontal plane as the axes of the pins 40 and in any one position of movement of the dial a pin is disposed with its axis at right angles to the axis of the cam shaft, for a purpose presently to more fully appear.

Upon the cam shaft there is secured an indexing cam 41 consisting of a body part 42, a reduced diameter spacing washer 43 and a circular plate 44, the three parts being positioned by a dowel 45 and secured by screws 46, the diameter of the plate being equal to the diameter of the inner end of the body and forming therewith a circular groove 47 having a width substantially corresponding to the diameter of the dial pins 40 for sliding engagement of the pins therein, and whereby the dial is locked against movement during a part of the rotation of the cam. The cam is fixed to the shaft 30 by a set screw 48.

In the cam illustrated by way of example, the part of its revolution during which it locks the dial is substantially seven-eighths, while the part of its revolution during which it moves the dial is substantially one-eighth. In this one-eighth part of the cam the body portion 42 is provided with a spiral slot 49, arranged in substantial concentricity to the periphery of the dial, and which extends from the groove 47 along the side of the body portion and into an extension portion 50 where the end of the slot is open in the direction of rotation of the cam to receive the successive pin to the pin engaged in the groove 47. The periphery of the body 42 and the extension portion 50 are substantially concentric to the curvature of the periphery of the dial 16, so that as the slot comes into engagement with the pin the latter moves in a concentric path through the slot from its entrance end to the groove 47. At the same time, the pin which has been locked in the groove 47 is allowed to move out of the groove, and for this purpose the plate 44 is provided with a gate opening 51 having its side walls disposed as a spiral in horizontal line with the starting portion of the spiral formation of the slot 49, so that as the succeeding pin starts its movement through the slot the pin that has been locked in the groove 47 moves out of the groove through the gate opening 51.

The cam is maintained in exact alignment with the axis of the dial by means of a plate 52 mounted upon a block

portion 53 of the platform 23 by means of screws 54, the width of the plate substantially corresponding to the width of the groove so that it has a sliding fit therein.

As shown clearly in Figs. 4-8, the spiral slot 49, as well as the gate opening 51, are generated so that their upper and lower surfaces are in parallel line contact with the pins as the latter travel therethrough, and due to the inclination of the slot and gate opening relative to the horizontal plane in which the pins move, the points of engagement of the wall surfaces of the slot and the gate opening with the pins are at points removed from the horizontally opposite surfaces of the pins. Thus, there is no wear upon these horizontally opposite surfaces and the pins will at all times fit perfectly within the locking groove 47 to prevent any looseness of the dial during its stationary periods.

In order to synchronize associated mechanisms with the indexing mechanism the cam shaft 30 may have suitable cams mounted thereon. Two such cams 55 and 56 are illustrated by way of example, and the cam 56 has a rocker arm 57 associated therewith, this rocker arm being provided in its hub end with a shaft 58 pivoted in a bearing portion 59 at the rearward end of the frame arm 22. A spring 60 presses a roller 61 into contact with the cam and at the end of the arm 57 there is pivotally connected a rod 62 for connection to a mechanism (not shown) to be actuated thereby.

In the event that the horizontally opposite side surfaces of the pins become worn to the point where they result in looseness in their engagement in the groove 47, the three part construction of the cam permits of convenient and inexpensive adjustment of the cam to compensate for such looseness, it being only necessary to either replace the washer 43 by one having a thickness dimension to substantially correspond to the horizontal width of the worn pins, or to grind or mill off a surface of the washer to obtain the proper dimensional fit.

While in the foregoing description the direction of indexing of the dial is clockwise and the direction of rotation of the cam is clockwise, as seen in Fig. 7, it is pointed out that the dial may be indexed in counter-clockwise direction by reversing the direction of rotation of the cam. In this case the extension portion 50 has a spiral cam surface 63 at its side opposite the slot 49, which initiates indexing movement of the dial by contacting the left hand pin 40, as seen, for instance, in Fig. 8, causing the pin 40 disposed in the groove 47, which at that point is at the right hand end of the slot 49, to enter the slot 49 and thereupon be moved thereby to the left, the pin 40 shown at the right in Fig. 8 passing through the opening 51 and entering the groove 47 at the same time that the pin in the slot 49 completes its movement therethrough.

It is pointed out that while the slot 49 and the opening 51 are illustrated as having a substantially close fit with the pins passing therethrough, such close fit is not essential, but there may be substantial looseness as only one side wall of the slot is in pressing engagement with the pin during its movement therethrough, and there is no necessity for contact of the side walls of the opening 51 with the pin passing therethrough.

What is claimed is:

1. In an indexing mechanism, a base frame, a dial rotatable about a central vertical axis fixed with respect

to said base frame, a circumferential series of equally spaced uniform diameter cylindrical pins carried by said dial having their outer ends disposed in a circumferential path of movement, their axes being radial to said vertical axis and coincident to a horizontal plane of rotation normal to said vertical axis, a cam rotatable about a horizontal axis fixed with respect to said base frame and coincident to said horizontal plane of rotation, said cam having a circumferentially continuous groove intersected by said circumferential path of movement of said outer ends of said pins and having a central vertical plane of rotation normal to said horizontal axis and radial to said vertical axis, said groove having inner and outer parallel walls in fixed spaced relation to each other and spaced apart a distance corresponding to the diameter of said pins, whereby said walls are respectively engageable by opposite sides of one of said pins with the axis of said engaged pin coincident to said vertical plane of rotation, said cam having a spiral slot having an entrance end open for engagement by the successive pin to the pin engaged in said groove and having an exit end in said inner wall opening to said groove whereby through rotation of said cam said successive pin moves through said slot and into said groove, said outer wall of said groove having an opening in substantial horizontal alignment with the entrance end of said slot through which a pin engaged in said groove moves out of said groove simultaneously with the initial movement of the successive pin through said spiral slot, and a cam aligning member fixed with respect to said base frame and disposed within said circumferentially continuous groove in engagement with said inner and outer walls thereof to restrain horizontal axial movement of said cam.

2. The indexing mechanism as defined in claim 1, wherein the said slot has opposed side walls, the surfaces of which are generated to engage opposite sides of a pin moving therethrough along lines parallel to the axis of said pin, said opposite sides being removed from the opposite sides engageable with the walls of said groove.

3. The indexing mechanism as defined in claim 1, wherein said opening of said outer wall of said groove is of spiral form substantially corresponding in pitch to the pitch of said spiral slot.

4. The indexing mechanism as defined in claim 1, wherein said cam comprises a rigid body part, a rigid plate part spaced therefrom and a rigid washer part interposed between said body part and said plate part, the opposed walls of said body and plate parts and the periphery of said washer part defining said circumferentially continuous groove.

5. The indexing mechanism as defined in claim 1, wherein said cam has a spiral cam surface in spaced relation to said spiral slot adapted through reverse rotation of said cam to engage one of said pins to initiate indexing movement of said pin engaged in said groove through said slot.
